(57) **CLAIM**

The ornamental design for a jewelry clasp, as shown and described.

DESCRIPTION

FIG. 1 is a right side and top perspective view of a jewelry clasp showing my new design;

FIG. 2 is a right side elevational view thereof, the left side elevational view being a mirror image thereof;

FIG. 3 is a front elevational view thereof;

FIG. 4 is a rear elevational view thereof;

FIG. 5 is a right side and top perspective view thereof, shown in an unclaimed environment;

FIG. 6 is a front view thereof, partially rotated from that which is shown in FIG. 3;

FIG. 7 is a right side and top perspective view of a second embodiment of a jewelry clasp showing my new design;

FIG. 8 is a right side elevational view thereof, the left side elevational view being a mirror image thereof;

FIG. 9 is a front elevational view thereof;

FIG. 10 is a rear elevational view thereof; and,

FIG. 11 is a rear elevational view thereof, partially rotated from that which is shown in FIG. 10.

The broken lines shown in the drawings represent environment and unclaimed portions of the jewelry clasp and form no part of the claimed design.
